US0D1059449S

(12) **United States Design Patent** (10) **Patent No.:** **US D1,059,449 S**
(45) **Date of Patent:** **** Jan. 28, 2025**

(54) **OIL PAN**

(71) Applicant: **Holley Performance Products, Inc.**,
Bowling Green, KY (US)

(72) Inventors: **Coy Hudnall**, Bowling Green, KY
(US); **Kevin Tracy**, Port Charlotte, FL
(US)

(73) Assignee: **Holley Performance Products, Inc.**,
Bowling Green, KY (US)

(**) Term: **15 Years**

(21) Appl. No.: **29/871,748**

(22) Filed: **Feb. 27, 2023**

Related U.S. Application Data

(63) Continuation of application No. 29/749,677, filed on
Sep. 8, 2020, now Pat. No. Des. 979,622.

(57) **CLAIM**

The ornamental design for an oil pan as shown and
described.

DESCRIPTION

FIG. 1 is an upper perspective view of an oil pan, showing
our new design;

FIG. 2 is a lower perspective view of the oil pan of FIG. 1;

FIG. 3 is a front view of the oil pan of FIG. 1;

FIG. 4 is a rear view of the oil pan of FIG. 1;

FIG. 5 is a first side view of the oil pan of FIG. 1;

FIG. 6 is a second side view of the oil pan of FIG. 1;

FIG. 7 is a top view of the oil pan of FIG. 1; and,

FIG. 8 is a bottom view of the oil pan of FIG. 1.

The broken lines show portions of an oil pan that form no
part of the claimed design.

1 Claim, 8 Drawing Sheets
